UNITED STATES PATENT OFFICE.

RUTH F. HOUGH, OF SOUTH PASADENA, CALIFORNIA.

DESIGN FOR A ROMPER.

59,844.

Specification for Design.

Patented Nov. 29, 1921.

Application filed March 24, 1921. Serial No. 455,164. Term of patent 7 years.

To all whom it may concern:

Be it known that I, RUTH F. HOUGH, a citizen of the United States, residing at South Pasadena, in the county of Los Angeles, State of California, have invented a new, original, and ornamental Design for a Romper, of which the following is a specification, reference being had to the accompanying drawing, forming part thereof.

Figure 1 is a front view of a romper showing my new design.

Fig. 2 is a reduced back view of the romper.

The essential feature of my design consists in providing, in a romper of the character indicated in the drawing, a back member having a flap at its lower edge of less width than the romper and extending upwardly

over the front member of the romper to about the level of the waist line, the flap narrowing toward its upper end.

Otherwise than as above indicated, the remaining appearance, outline, construction or ornamentation of a romper to which my design has been applied is immaterial as to my design.

Having thus described my invention, I claim:

The ornamental design for a romper, substantially as described and shown.

Signed at Los Angeles, California, this 17th day of March, 1921.

RUTH F. HOUGH.
